CLAIM

The ornamental design for a modeling block, as shown and described.

DESCRIPTION

FIG. 1 is a front orthogonal view of a modeling block showing the new design;

FIG. 2 is a front view of the invention illustrated in FIG. 1; FIG. 3 is a rear view of the invention illustrated in FIG. 1; FIG. 4 is a right side view of the invention illustrated in FIG. 1;

FIG. 5 is a left side view of the invention illustrated in FIG. 1;

FIG. 6 is a top view of the invention illustrated in FIG. 1; FIG. 7 is a bottom view of the invention illustrated in FIG. 1; and,

FIG. 8 is another orthogonal view of the invention illustrated in FIG. 1.

The broken lines in the drawings depict portions of the modeling block that form no part of the claimed design.
